INVENTOR.

Joseph J. Primeau
BY

William E. Raff ATTORNEY.

UNITED STATES PATENT OFFICE.

JOSEPH J. PRIMEAU, OF WORCESTER, MASSACHUSETTS.

COMBINED COAT AND HAT HANGER.

1,389,218.

Specification of Letters Patent. Patented Aug. 30, 1921.

Application filed February 2, 1921. Serial No. 441,986.

To all whom it may concern:

Be it known that I, JOSEPH J. PRIMEAU, a citizen of the United States, and a resident of the city of Worcester, in the county 5 of Worcester and State of Massachusetts, have invented new and useful Improvements in Combination Coat and Hat Hangers, of which the following is a specification.

This invention relates to improvements in 10 garment supports and more particularly to combination coat and hat hangers.

One of the objects of my invention is to provide a simple, efficient, inexpensive device of the character described which shall 15 be made in such a way as to permit the coat hanger to collapse into a small compass.

A further object of my invention consists 20 in providing in combination with a sheet metal hanger means for supporting or suspending said hanger in position upon a wall support or abutment with ease and despatch.

A still further object of my invention, is 25 to provide in a device as described a hanger having means adapted to serve the two-fold function of taking a secure foothold or anchorage upon any suitable abutment or support and also to permit a pair of foldable arms forming a coat hanger to engage said means so as to hold and lock said arms in 30 fixed position.

A still further object of my invention consists in providing a sustaining or supporting hanger with an integral hook upon which a cap is adapted to rest and be supported.

And it is another object of my invention 35 to provide a combination coat and hat hanger equipped with an integral hat supporting hook and also supporting coat hanger in collapsible relation thereto, the arrangement of the parts being such that the device may be used either as a hat hanger or coat hanger or both and in either event the device is provided with integral means 45 by which it is possible for a person to fasten the same with extraneous means upon any support such as the window sill, a wall, a door, or outdoors upon a tree, line, etc.

With the above and other objects in view 50 my invention consists in the combination, arrangement and details of construction

herein disclosed in the drawings and specification and then more particularly pointed out in the appended claims.

In the drawings which are merely illustrative of my invention, similar reference characters are designated by similar figures throughout the respective views.

Figure 1 is a front elevation of my invention supported in position, 60

Fig. 2 is a rear elevation thereof,

Fig. 3 is a side elevation thereof in position,

Fig. 4 is a perspective view thereof,

Fig. 5 is a side view of one of the coat hanger arms, 65

Fig. 6 is a bottom plan view of my invention,

Fig. 7 is a detail fragmental view thereof,

Fig. 8 is a detail fragmental, sectional 70 view of a pivotal support,

Fig. 9 is a plan view of a sheet metal blank stamped out to provide a hanger,

Fig. 10 is a rear elevation of my invention with all the parts collapsed, 75

Fig. 11 is a bottom plan view of Fig. 10,

Fig. 12 is a top plan view of Fig. 10,

Fig. 13 is a side view of Fig. 10, and,

Fig. 14 is a front elevation of Fig. 10.

In the drawings which are merely illustrative of my invention A designates any given support upon which my hanger is adapted to be mounted. 1 and 2 designates similarly sized and shaped coat hanger arms which may be made of metal, wire or any other suitable material and which may optionally be formed short of their inner ends with the loops 3 and also at their outer ends with the hooks or loops 4 and terminal ball tips 5 the inner ends of the arms 1 and 2 are perforated as at 6 for the reception of a pivot pin 17, the overlapping inner pivoted ends of both arms 1 and 2 being designated 7 and 8 as shown in Figs. 6 and 8 particularly, and being preferably beveled 95 at these points to make a lap joint.

In order to provide a suitable hanger to support the coat hanger sheet metal may be used and a blank such as shown in Fig. 9 stamped out so as to provide the elongated strap 9 one end of which is slit as at 22 to provide the opposing divergent arms

18 and 19 and V recess B. The strap 9 is adapted to undergo the operation of folding by which a hook 12 is performed in the nature of a loop portion the bight end of 5 which is designated 11 and the side portions of which are designated respectively 10 and 13 and the end of the strap below the hook 12 is designated 14, being in line with the strap 9 and formed into a loop 15 10 with a reversely bent hook portion 16 in which the pivot pin 17 is secured upon which are supported the coat hanger arms 1 and 2. It will be seen that the arms 1 and 2 extend downwardly in opposite directions 15 in such a way as to maintain the usual appearance of a coat hanger.

The arms 1 and 2 are maintained in a horizontal position when open and readily supporting the coat by reason of the fact 20 that their inner ends rest upon the loop 15 at the lower end of the strap 9 as shown in Figs. 1, 2 and 4. The arms 18 and 19 of the strap 9 are provided with the hook spurs 21 which extend downwardly and 25 which may take a secure foothold and anchorage in any support such as the support A thereupon a hat may be placed upon the hook 12 and a coat upon arms 1 and 2 and the shape of these articles will be main- 30 tained intact thus a person is able instantly to set up the coat hanger without any special fastener.

If it is desired to collapse the parts of this device into a small space this can readily be 35 done as will now be explained. Then with the metal blank which will preferably be made of spring metal so that the various parts may readily yield, this being the case after the arms 1 and 2 are folded up- 40 wardly upon the pivot 17 the strap 9 may be readily flexed over diagonally of the side arms as shown clearly in Fig. 13 until the hook spurs 21 spring over around and against these arms and lock them in a neat 45 folded and collapsed relation the parts will look as particularly shown in Figs. 10 to 14 inclusive. It is still to be noticed that when the parts are thus collapsed and the arms are held against collapsation by means 50 of hook spurs 21 that there will still be another clearance between the spurs 21 and the side arms 1 and 2 to permit the spurs to be sunken in any support and thus the device is ready to use as a hat hanger alone 55 as shown clearly in Fig. 13.

This device is equally well adapted as a hat hanger or a coat hanger or both and when the parts are all folded together the device may be readily carried around in 60 the pocket of the user and instantly set up and positioned to support a coat and hat in the manner of any coat hanger having the added advantage of a hat hanger.

Numerous modifications may be resorted

to in practice without departing in principle from the details of construction herein disclosed.

Claims:

1. A device as described consisting of a sheet metal strap being slit at one end to 70 provide oppositely extending arms, hook spurs formed terminally upon said arms and a pair of coat hanger arms pivoted to the lower portion of said hanger and adapted to be folded up and sprung into said hook 75 spurs.

2. A device as described consisting of a sheet metal hanger being provided with a pair of divergent arms formed with terminal spurs, a pair of coat hanger arms pivotally 80 carried by said hanger and of a length to engage said spurs so as to extend alongside said hanger in collapsed relation thereto.

3. A device as described consisting of a sheet metal strap being slit at its upper end 85 to provide a pair of divergent arms formed with terminal spurs the strap being formed at its lower end with another hook and a pair of coat hanger arms having their inner ends pivoted upon the last named hook and 90 having their outer ends foldable alongside said strap and engageable with said spurs.

4. A device as described consisting of a sheet metal strap slit at one end to provide a pair of divergent arms a pair of hook 95 spurs formed upon said divergent arms, said strap being formed between its ends with a looped hook and a pair of coat hanger arms pivoted upon said hanger below said hook and having their outer ends adapted to fold 100 within the spurs of the strap.

5. A sheet metal hanger made of spring metal formed at one end with a pair of yieldable arms having terminal spurs, an intermediate looped hook formed upon said hanger 105 and a pair of coat hanger arms having their inner ends pivotally secured upon said hanger and having hook terminals adapted to be positioned within said spurs so as to lock said arms in collapsed position.

6. In combination a sheet metal strap, a pair of coat hanger arms pivotally connected at one end to said strap and a pair of hook shaped spurs carried by said strap at its opposite end and serving a two-fold 115 purpose of supporting said strap and receiving the ends of said arms so as to lock the same in collapsed relation.

7. A device of the kind described consisting of a sheet metal strap formed of spring 120 metal and slit at its upper end to provide opposing arms, the upper end of said arms being bent, terminal spurs extending downwardly from the bent ends of said arms, the lower portion of said strap being provided 125 with a hook portion, a pair of coat hanger shaped arms pivoted to the last named hook portion, a common pivot for said arms se-

cured to the last named hook, the said strap adapted to be flexed diagonally of said arms and between them so as to connect the bent upper end around said arms to frictionally lock them in position, said arms when released from said spurs adapted to fold in a horizontal position.

8. A device as described consisting of a sheet metal strap providing a pair of opposing hooks spurs at its upper end and a coat

hanger having oppositely extending arms and connected centrally to the lower end of said hanger.

In witness whereof I have hereunto set my hand and seal this 1st day of February, 1921. 15

JOSEPH J. PRIMEAU. [L.s.]
